UNITED STATES PATENT OFFICE.

SAMUEL M. LINES, OF INDIANAPOLIS, INDIANA.

CLASP.

SPECIFICATION forming part of Letters Patent No. 382,480, dated May 8, 1888.

Application filed February 27, 1888. Serial No. 265,402. (No model.)

To all whom it may concern:

Be it known that I, SAMUEL M. LINES, a citizen of the United States, residing at Indianapolis, in the county of Marion and State 5 of Indiana, have invented a new and useful Improvement in Clasps, of which the following is a specification.

My invention relates to an improvement in that class of clasps which consist of a pair of 10 sheet-metal plates having lugs and serrated jaws formed integral therewith, a pivot passing through said lugs, and a coiled spring mounted on the pivot, whereby the jaws are forced together.

15 The object of my improvement is to provide improved means for securing a clasp of the class mentioned to the clothing for the purpose of holding a napkin, handkerchief, or other like article.

20 The accompanying drawings illustrate my invention.

Figure 1 is a view in perspective. Fig. 2 is a longitudinal section at *a*, Fig. 1. Fig. 3 is a view in perspective, on an enlarged scale, of 25 the spring.

The jaws of the clasp are formed of two

plates, A and B, having lugs *c d* formed integral therewith, which jaws are connected by a pivot, *e*, and are forced together at their gripping ends by a coiled spring, *f*, mounted 30 on the pivot in the usual well-known manner.

For the purpose of conveniently attaching this clasp to a garment, I secure to the under plate, B, a sharpened hook, *h*. Hook *h* is formed of wire integral with the coiled spring 35 *f*, and is secured in place by bending up the rear portion of jaw B and passing the hook through an opening in said bent-up portion, as shown at *i*, before putting in the rivet *e*.

With a clasp constructed in the manner described a napkin or handkerchief may be 40 quickly attached to the clothing.

I claim as my invention—

In a clasp, the combination, with the gripping jaws, the pivot, and the coiled spring 45 mounted on the pivot, of the hook formed integral with the spring and secured to the jaws, substantially as and for the purpose specified.

SAMUEL M. LINES.
